Attorney

UNITED STATES PATENT OFFICE.

BURT EMRICK, OF JACKSON, MICHIGAN.

BOTTLE-CLOSURE.

1,348,273.

Specification of Letters Patent. Patented Aug. 3, 1920.

Application filed December 29, 1919. Serial No. 347,971.

To all whom it may concern:

Be it known that I, BURT EMRICK, a citizen of the United States, residing at Jackson, in the county of Jackson and State of Michigan, have invented certain new and useful Improvements in Bottle-Closures, of which the following is a specification, reference being had to the accompanying drawings.

10 This invention relates to certain improvements in bottle closures, and has relation more particularly to a device of this general character especially designed and adapted for use in connection with milk bottles or the like, and it is an object of the invention to provide a novel and improved device of this general character which may be readily and detachably engaged with the bottle, and which is provided with a closing disk supported in a manner whereby the disk readily centers itself when applied within the neck.

Another object of the invention is to provide a novel and improved device of this general character which is adapted to be used after the paper cap or the like which is generally applied to the bottle has once been removed and wherein the closing or sealing disk comprised in the device may be effectively maintained in closed position and readily moved into an open position when it is desired to pour out the contents of the bottle or a portion thereof.

An additional object of the invention is to provide a novel and improved device of this general character comprising a split resilient ring adapted to conform to the bead on a bottle neck and circumferentially embrace and clamp said bead together with a handle member pivotally mounted upon the ring and having loose connection with a closing or sealing disk, thus allowing the disk to center itself when applied to the bottle and wherein the sliding connection between the handle member and the disk includes means to facilitate the requisite movement of the disk when centering itself within a bottle.

The invention consists in the details of construction and in the combination and arrangement of the several parts of my improved bottle closures whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in side elevation illustrating a bottle closure constructed in accordance with an embodiment of my invention and in applied 65 position.

Fig. 2 is a view in top plan of the structure as illustrated in Fig. 1.

Fig. 3 is a view in rear elevation of my improved bottle closure unapplied; and 70

Fig. 4 is a view in plan of the spring member as included herein.

As disclosed in the accompanying drawings, 1 denotes a one piece split resilient ring adapted to conform to the bead on a 75 bottle neck and circumferentially embrace and clamp said bead. Riveted or otherwise secured to the outer face of said ring 1 at a point substantially midway thereof is an outstanding ear or wing 2. The ear or wing 2 extends between the side members *a* of a substantially U-shape member or bracket 3, and said ear or wing 2 is pivotally engaged with said side members *a* through the instrumentality of the rivet 4 or the like. The intermediate or central portion *b* of the member or bracket 4 is riveted or otherwise secured to an end portion of a handle member 5. The handle member 5 has its opposite end portion disposed on an outward curve with 80 respect to the bottle B when applied, and terminates in a point 6 whereby said handle member 5 may be employed to remove from the bottle B a paper cap or the like initially applied to the bottle. 85

The end portion of the handle member 5 with which the member or bracket 3 is secured is continued by an angularly disposed extension or arm 7 having its outer end portion inwardly offset with respect to the 90 handle member 5 and terminating in a foot 9. The foot 9 is provided with a slot 9^a extending in a direction longitudinally of the extension or arm 7 and through which is slidably disposed a rivet 10 or the like, and which rivet 10 is also operatively engaged with the axial center of the sealing or closing disk 11. The rivet 10 is also disposed through the axial center or a concavo-convex washer or plate 12 in substantially the 100 105 110

form of an equi-lateral triangle in plan. The washer or plate 12 has its convex face disposed in a direction toward the foot 9 and whereby the washer or plate 12 has contact 5 with the sealing or closing disk 11 at three points.

With the ring 1 properly engaged with the bead of the bottle B, and upon movement of the arm or extension 7 toward said 10 bottle, the sealing or closing disk 11 will properly center itself with respect to the neck of the bottle, and which movement is afforded by the slot 9^a and materially facilitated by the washer or plate 12.

15 When my improved device is in applied position on the bottle B, the disk 11 is constantly urged toward the internal seat within in the neck of the bottle by the spring S. As herein disclosed, the spring S is formed 20 with a single strand of material returned upon itself to provide the side members C, and each of which side members C is bent to provide the coils D. When the spring S is in applied position, the coils embrace or 25 encircle the rivet 4 at opposite sides of the ear or wing 2. The returned portion of the strand bears against the handle member 5, while the free extremities of the strand bear against the ring 1. By this means, the handle member 5 is constantly urged in a direction 30 away from the bottle when the device is in applied position and the extension or arm 7 of said handle member constantly urged toward the bottle.

35 It is also preferred to interpose between the outer head of the rivet 10 and the foot 9 the washer 14 and which washer circles or surrounds the rivet 10 and is of a major diameter in excess of the width of the slot 9^a.

40 From the foregoing description, it is thought to be obvious that a bottle closure constructed in accordance with my invention is particularly well adapted for use by reason of the convenience and facility with 45 which it may be assembled and operated, and it will also be obvious that my invention is susceptible of some change and modification without departing from the principles and spirit thereof, and for this reason

I do not wish to be understood as limiting myself to the precise arrangement and formation of the several parts herein shown in carrying out my invention in practice except as herein claimed.

I claim:

1. A closure for bottles comprising a split ring adapted to engage about a bottle, a handle member pivotally carried by said ring, a disk, a headed member carried by the disk, said handle member being provided with a slot through which said member is directed, and a concavo-convex plate interposed between the handle member and the disk and through which the headed member is also directed whereby said disk is pivoted for angular oscillation with relation to said foot. 55

2. A closure for bottles comprising a split ring adapted to engage about a bottle, a handle member pivotally carried by said ring, 70 a disk, a headed member carried by the disk, said handle member being provided with a slot through which said member is directed, and a concavo-convex plate interposed between the handle member and the disk and through which the headed member is also directed, the convex face of said plate being disposed in a direction toward the handle member whereby said disk is pivoted for angular oscillation with relation to said foot. 75

3. A closure for bottles comprising a split ring adapted to engage about a bottle, a handle member pivotally carried by said ring, a disk, a headed member carried by the disk, said handle member being provided with a slot through which said member is directed, and a concavo-convex plate interposed between the handle member and the disk and through which the headed member is also directed, the convex face of said plate being disposed in a direction toward the handle member, said plate being substantially triangular in plan whereby said disk is pivoted for angular oscillation with relation to said foot. 80

In testimony whereof I hereunto affix my signature.

BURT EMRICK.
